RECOIL CHECK AND BARREL ACCELERATOR
FOR A MACHINE GUN

Samuel G. Green, Gray, Ga.

Application August 23, 1937, Serial No. 160,465

3 Claims. (Cl. 89—14)

(Granted under the act of March 3, 1883, as
amended April 30, 1928; 370 O. G. 757)

The invention described herein may be manufactured and used by or for the Government for governmental purposes, without the payment to me of any royalty thereon.

This invention relates to a recoil check and barrel accelerator for a machine gun.

The purpose of the invention is to provide a recoil check and barrel accelerator which is especially adapted for the type of barrel mounting shown in my Patent No. 2,026,528 of January 7, 1936, and involves an arrangement of a baffle with respect to the barrel whereby the discharge of high pressure and high temperature gases is controlled by a restricted passage and so directed as to prevent the accumulation of carbon and fouling of the bearing for the barrel.

To these and other ends, the invention consists in the construction, arrangement and combination of elements described hereinafter and pointed out in the claims forming a part of this specification.

A practical embodiment of the invention is illustrated in the accompanying drawing, wherein:

Fig. 1 is a longitudinal sectional view of the front of a machine gun constructed in accordance with the invention and showing the barrel in battery.

Fig. 2 is a similar fragmentary view showing the barrel in full recoil.

Fig. 3 is a detail view in side elevation of the gland and extension.

Fig. 4 is a sectional view on the line 4—4 of Fig. 1.

Referring to the drawing by characters of reference there is shown the front portion of a machine gun comprising a barrel 5 which is disposed in a jacket 6 adapted to contain a cooling medium. A front end cap 7 on the jacket is

formed with a fixed cylindrical sleeve 8 having a reduced internal diameter at its inner end to provide a bearing 9 for supporting a movable sleeve 10. The sleeve 10 has a front inturned end 11 threaded to the muzzle of the gun barrel

and serving to space the body of the sleeve from the barrel for the purpose of enabling the cooling medium to be in direct contact with the front end of the barrel. In the normal "in battery" position of the barrel its front end does not project beyond the face of the end cap. The sleeve 10 however projects a slight distance beyond the cap and has a beveled face 12 to provide a flaring mouth.

A gland 13 disposed within and threaded to the end cap 7 serves as a support or bearing for the

front part of the sleeve 10 and also confines a ring 14 which is between the sleeve and bearing and holds a packing ring 15 against the front wall of the bearing 9. The gland includes a tubular extension 16 having an internal diameter greater than that of the gland so that it will be appreciably spaced from the projecting end of the sleeve 10. The inner portion of the extension 16 which is adjacent the end cap is provided with a plurality of annularly arranged ports 17.

The outer portion of the extension is threaded internally for attachment of a plug or baffle 18. The baffle is formed with an axial bullet passage 19 having a flared entrance 20 which is spaced from the front face of the barrel. The rear part 15 of the baffle is conical, its apical portion 21 disposed within and spaced from the flared mouth of the sleeve 10 to form a normally restricted gas passage 22 and its wall 23 meeting the extension on a line with the forward wall of the ports 17.

When a bullet fired from the gun leaves the barrel and enters the baffle the barrel has just started its recoil movement and has traveled to the rear about one-sixteenth of an inch. It is at 25 this stage that the high pressure and the high temperature gases immediately following the bullet impinge on the baffle and react on the front face of the barrel to assist in driving the barrel rearwardly and thereby accelerate its movement 30 and the resulting rate of fire. At the same time the action of the gases on the baffle tends to move the jacket 6 forwardly and counteract the forces of recoil exerted on the jacket and the mount (not shown). A portion of the high pressure and 35 high temperature gases are vented through the ports 17, the restricted passage 22 between the baffle and the sleeve insuring the maintenance of a sufficiently high pressure to prevent the accumulation of carbon. The forcible discharge 40 of the gases at this stage creates a vacuum on the outer side of the projecting end of the movable sleeve 10 and thereby prevents fouling of the bearing formed by the gland.

As the barrel continues on its recoil stroke of 45 one and one-eighth inches the front edge of the sleeve recedes into the gland (Fig. 2), thereby enlarging the annular passage between the baffle and sleeve and facilitating the discharge of the remaining low pressure gases from the barrel.

I claim:

1. In a machine gun, a jacket having a front end cap with a bearing, a gun barrel mounted for reciprocation in the jacket and normally having its muzzle within the end cap, a sleeve 55

- on the barrel and supported in the bearing, the end of the sleeve projecting beyond the end cap, and having a beveled face forming a flared mouth, a gland threaded in the cap and supporting the sleeve, a tubular extension on the gland spaced from the sleeve and having a plurality of ports in its inner end, a baffle fixed in the outer end of the extension and having a conical inner end disposed within the flared mouth of the sleeve and spaced from the front of the barrel and the beveled face of the sleeve to provide a normally restricted gas passage, said baffle having a bullet passage with a flared entrance for reflecting gases onto the barrel.
5. In a machine gun, a jacket having a front end cap, a gun barrel mounted for reciprocation in the jacket, a sleeve fixed on the end of the barrel and slidably supported in the end cap, said sleeve having a flared mouth normally projecting from the end cap when the barrel is in battery and movable into the end cap when the barrel is in recoil, a supporting member fixed to the end cap in laterally spaced relation to the sleeve and having ports, and a baffle carried by
10. 2. In a machine gun, a jacket having a front end cap, a gun barrel mounted for reciprocation in the jacket, a sleeve fixed on the end of the barrel and slidably supported in the end cap, said sleeve having a flared mouth normally projecting from the end cap when the barrel is in battery and movable into the end cap when the barrel is in recoil, a supporting member fixed to the end cap in laterally spaced relation to the sleeve and having ports, and a baffle carried by
15. 3. In a machine gun, a jacket having a front end cap, a gun barrel mounted for reciprocation in the jacket, a sleeve fixed on the end of the barrel and slidably supported in the end cap, said sleeve having a flared mouth normally projecting from the end cap when the barrel is in battery and movable into the end cap when the barrel is in recoil, a supporting member fixed to the end cap and having ports, and a baffle carried by said member and having a bullet passage and an inner end shaped complementary to the flared mouth of the sleeve, said inner end disposed within the flared mouth of the sleeve and cooperating therewith to form a normally restricted gas passage.

5. said member and having a conical inner end disposed within the flared mouth of the sleeve and normally spaced a slight distance from the flared mouth of the sleeve to provide a normally restricted gas passage, said baffle having a bullet passage with a flared entrance for reflecting gases onto the barrel.

10. 3. In a machine gun, a jacket having a front end cap, a gun barrel mounted for reciprocation in the jacket, a sleeve fixed on the end of the barrel and slidably supported in the end cap, said sleeve having a flared mouth normally projecting from the end cap when the barrel is in battery and movable into the end cap when the barrel is in recoil, a supporting member fixed to the end cap and having ports, and a baffle carried by

15. 3. In a machine gun, a jacket having a front end cap, a gun barrel mounted for reciprocation in the jacket, a sleeve fixed on the end of the barrel and slidably supported in the end cap, said sleeve having a flared mouth normally projecting from the end cap when the barrel is in battery and movable into the end cap when the barrel is in recoil, a supporting member fixed to the end cap and having ports, and a baffle carried by

20. 3. In a machine gun, a jacket having a front end cap, a gun barrel mounted for reciprocation in the jacket, a sleeve fixed on the end of the barrel and slidably supported in the end cap, said sleeve having a flared mouth normally projecting from the end cap when the barrel is in battery and movable into the end cap when the barrel is in recoil, a supporting member fixed to the end cap and having ports, and a baffle carried by

SAMUEL G. GREEN.
